PORABLE WHIRLPOOL BATH

Clifford E. Grube, Niles, Ill., assignor to Associated Mills, Incorporated

Filed Mar. 26, 1973, Ser. No. 345,008

Term of patent 14 years

Int. Cl. D24—04

U.S. Cl. D83—1 C

FIG.1

FIG.5

FIG. 1 is a perspective view of the portable whirlpool bath showing my new design;

FIG. 2 is a top plan view thereof;

FIG. 3 is one side view thereof, the other side view thereof being substantially identical;

FIG. 4 is one end view thereof; and

FIG. 5 is the other end view thereof.

I claim:

The ornamental design of a portable whirlpool bath, as shown and described.
